[57] CLAIM

The ornamental design for a portative holder for separate extension cords, as shown and described.

DESCRIPTION

FIG. 1 is a left side, top and front perspective view of a portative holder for separate extension cords showing my design in open, relaxed posture with VELCRO attachment members in flat array;

FIG. 2 is a left side, top and front perspective view thereof in wrapped around posture, the side opposite being substantially a mirror image;

FIGS. 3A, 3B and 3C are left side, top, and front perspective views of the portative holder in respective sundry, wrapped postures;

FIGS. 4 and 5 are respective, flattened out top and bottom plan views thereof;

FIG. 6 is a front elevational view thereof, when not in use, the rear elevational view being a mirror image;

FIG. 7 is an end elevational view thereof, the opposite end being a mirror image; and

FIG. 8 is an enlarged side elevational view of FIG. 6, the rubber member being in non-stretched posture.

The broken line showing of separate, individual extension cords in FIGS. 2, 3A, 3B, 3C, 4 and 5 is for illustrative purposes only and forms no part of the claimed design.
